UNITED STATES PATENT OFFICE.

GRANT RONEY, OF SWALEDALE, IOWA.

VETERINARY FORCEPS.

Application filed April 8, 1926. Serial No. 100,680.

This invention relates to new and useful improvements in veterinary instruments, and particularly to such instruments which are used in obstetrical cases.

5 One object of the invention is to provide a device of this character which includes means for projecting a light into the cavity of the animal, whereby to permit the veterinarian to see the position of the jaws of 10 the forceps, with relation to the foetus.

Another object is to provide a device of this character which is equipped with a reflecting means which permits the operator to gain a clear view of the interior of the 15 cavity being operated upon, and which is illuminated by an electric lamp carried by the cavity entering end of the device.

Other objects and advantages will be apparent from the following description when 20 taken in connection with the accompanying drawing.

In the drawing:

Figure 1 is a side elevation of an obstetrical instrument made in accordance 25 with the present invention.

Figure 2 is a vertical longitudinal central sectional view through the device.

Figure 3 is a horizontal longitudinal sectional view on the line 3—3 of Figure 1.

30 Referring particularly to the accompanying drawing, 10 represents a tube having a longitudinal slot 11 adjacent one end, and a transversely extending bar 12 in the other end, said last-named member 12 having a short tube 13 extending therethrough, and 35 having the pair of openings 14, for the reception of the shanks of the jaws 15, of the instrument. Within the said tube 13 is mounted an electric lamp 16, which receives 40 current from a battery located in a casing 17 mounted on the other end of the tube 10. The inner ends of the shanks of the jaws 15 are pivotally connected with the adjacent end of a block 18, which slides longitudinally within the tube, a bolt 19 being carried by the other end of said block and playing in said slot 11. To this bolt, externally of the tube 10, there is connected a suitable handle 20, which is grasped by the veteri-

narian, whereby to permit longitudinal sliding movement to be imparted to the block 18. The shanks of the jaws diverge outwardly, and when the block is moved toward the end of the tube 10 the jaws will move away from the end of the tube, and also away from each other. When, however, the block is moved in the other direction the shanks will be moved into the tube and the jaws move toward each other so that they may firmly grip the head of the foetus therebetween. Thus, by moving the handle 20 longitudinally of the slot 11, the operator can cause the jaws of the device to open or close to the desired position. At the same time, the electric light permits the cavity to be clearly illuminated.

55 Fitted in the slotted end of tube 10 is a tube 20 in which is mounted an oblique mirror, shown at 21, and visible to the operator through an opening 22 in one side of the tube 20. The illuminated cavity is plainly visible in the mirror 21, so that the operator 60 may readily see how to manipulate the jaws of the forceps.

65 What is claimed is:

A veterinary forceps comprising a tubular handle portion having a longitudinal slot adjacent one end, a centrally arranged block in the other end of the handle portion, a longitudinal rod in the handle, a handle member carried by one end of the rod and extending outwardly through said slot, a pair of superimposed plates secured to the other end of the rod, and a pair of forceps jaws pivotally mounted between said plates and extending outwardly through the tubular handle portion between the said block and the side walls of the said handle portion, said handle member being adapted to be grasped to move the rod and project and withdraw the forceps jaws with relation to the end of the tubular handle portion whereby to engage the shanks thereof in spreading relation with the block.

70 In testimony whereof, I affix my signature.

GRANT RONEY.
